H. A. AGRICOLA, JR.

PRINTING PRESS ATTACHMENT

Filed March 27, 1924

UNITED STATES PATENT OFFICE.

HERMAN ADOLPHUS AGRICOLA, JR., OF ATLANTA, GEORGIA, ASSIGNOR OF FORTY-NINE PER CENT TO JOSEPH E. LANE, OF ATLANTA, GEORGIA.

PRINTING-PRESS ATTACHMENT.

Application filed March 27, 1924. Serial No. 702,258.

The present invention has reference to printing presses having multi-color attachments of the general kind set forth in my application Serial No. 636,371 which was filed May 3, 1923.

The features constituting my invention are designed for embodiment in one or more units which may be conveniently attached to a printing press of standard type whereby it is adapted to perform chromatic printing. This invention effects the above result by the employment of a movable carriage whereon are mounted roller systems in which are included inking and form rollers to which rotation may be imparted by any suitable means; also by the employment of an inking plate in which are assembled a plurality of pinions adapted to be intermittently rotated, the several pinions being disposed flush with the working face of the plate so as to co-operate therewith in distributing ink of one or more colors over certain selected form rollers, or desired portions thereof; and also by the provision of one or more stationary inking fountains which are adjustable in relation to the inking plate whereby ink of one or more colors may be delivered to the inking rollers for transference to certain selected pinions of the inking plate, and from thence to certain selected portions of the form rollers, which, in turn, apply the individual ink colors to desired portions of the form. The invention consists further in numerous other features of construction and combinations of parts as will more clearly hereinafter appear from the specification and claims, taken in conjunction with the accompanying drawings, wherein the present improvements are illustrated in the manner following:

Fig. 1 is an end elevation of the upper portion of a printing press whereon the form rollers execute a movement around a bend or curve, certain of the present improvements being applied to this type of press; and

Fig. 2 is a front elevation thereof.

The press herein shown is equipped with a pair of connected arms F which oscillate about a pivot 50. Formed on each of these arms are two pairs of guides 51 and 52 wherein are slidably received rods 53 and 54, respectively, each equipped with a compression spring 55. At their outer ends the two rods 54 are suitably formed to provide bearings for a form roller 56. The other rods 53

are connected with a truck 57 in which are journaled other form rollers 58 and 59, also a sectional vibratory roller 60. Pivoted to the truck is a frame 61 in which is journaled a brayer or inking roller 62, preferably of lesser diameter than the form rollers just described. The inking roller is equipped at its ends with a pair of wheels 63 of slightly greater diameter adapted to ride upon suitable guides or rails upon the sides of the press. A contraction spring 64 connects the inking roller frame 61 with the arm F so as to normally hold the wheels 63 in firm contact with the rails whereon they are designed to travel.

The ink distributing plate E is shown as provided with a plurality of meshing pinions 24 which are adjustably arranged in groups and adapted to be revolved through a common drive. As indicative of one means which is suitable for this purpose, I have shown several of these pinions as each provided with a ratchet wheel 65 which extends through to the underside of the ink distributing plate; associated with this ratchet is a dog 66, and connecting these several dogs is a linkage 67 from which is downwardly projected a stem 68. A limited reciprocatory movement is imparted to this stem through the medium of two pins 69 and 70 carried on an arm 71 which extends between the two extremities of a bell crank lever 72 pivoted to the press as at 73 for rocking movement beneath the ink distributing plate. One end of the bell crank lever may be provided with a roller 74 for engagement with a cam 75 that is positioned on one rocking arm F. By the means described, each rocking movement of the arm F will cause the bell crank lever to be rocked with the consequence that the two pins 69 and 70 will alternately move the stem 68 to thereby reciprocate the linkage 67, the result being that the several ratchets 65 are intermittently rotated to effect a like movement on the part of each ink distributing pinion 24.

For imparting rotation to the rod 27 whereon the inking fountains are positioned, a connection of the kind shown in Fig. 1 may be used. This includes a link 76 extending from the arm 71 to the arm 33 which is loosely pivoted on the rod 27. It follows that with each rocking of the bell crank lever, the arm 33 will likewise be moved for a distance sufficient to impart an intermittent

movement to a ratchet wheel secured to this rod whereby the fountain rollers 28 are given a desired movement.

A press having the equipment shown in Figs. 1 and 2, will operate in substantially the manner just explained. With each rocking movement of the arms F, the form rollers are caused to travel back and forth between the form and ink distributing plate. During these operations the form rollers, as well as the inking roller, will execute an angular movement around the bend 77, the rods 53 and 54 being yieldably mounted and the several rollers being linked so as to permit of such movements. The inking roller 62 is held away from the form at all times due to the greater diameter of its wheels 63, but upon passing around the bend 77 these wheels will descend upon an incline 78 to a point of lower elevation permitting the inking roller to come into contact with the ink distributing plate. Throughout the rest of this movement, the inking roller remains in contact with the several disks 24 and eventually engages with the inking fountains to receive therefrom a supply of ink. The ink distributing plate which in Fig. 6 is shown with its two end sections separated may have its meeting edges toothed or otherwise formed as at 79 so as to dovetail or interfit when these plate sections are moved together. This is of advantage in one color printing as thereby I eliminate the formation of any ink line which would otherwise develop on the rollers to the detriment of an even distribution of ink thereupon.

I would have it noted that the attachments of this invention may be readily applied to various kinds of standard printing presses, of which one suggestive type is illustrated in the drawing. By employing an inking plate having a plurality of adjustable pinions, and associating therewith a pair of adjustable inking fountains, I am able to provide for an unmixed transference of two inking colors to suitable form rollers, the result being that the form is inked with the two colors at only the desired places. The several mechanisms just described derive motion from the moving parts of the press, being operatively connected therewith in a very simple and effective manner. If, for any reason, it is desired to change over from chromatic to one-color printing, the original inking plate, form rollers, etc., may be replaced on the press, with the expenditure of but little effort and time.

I claim:

1. In a printing press, the combination of a form and an inking plate disposed in an

angular relation to each other, a pair of connected oscillating arms mounted on the press, a truck yieldingly mounted between the arms having wheels adapted to travel along the press sides and around a bend thereupon, a form rollers associated with the truck, a frame pivoted to the truck, a brayer mounted in the frame, wheels associated with the brayer adapted to ride upon the press sides and to prevent contact between the brayer and the form, the surfaces whereon the wheels ride being so formed as to permit the brayer to engage with the inking plate, an inking fountain associated with the plate, and an operative connection between the fountain and the oscillating arms such that movement is communicated from the latter to the former, substantially as described.

2. A printing press having, in combination, a form and an inking plate in angular relation, the plate being provided with a plurality of rotatable pinions, a plurality of inking fountains associated with the plate, a common rod whereon the fountains are adjustably mounted, a driving connection between the rod and the several pinions, a form roller and a brayer adapted for angular travel back and forth between the form and inking plate, means for causing such movement of the form roller and brayer, and a connection from said means to the driving connection between the pinions and rod whereby an intermittent rotation is imparted thereto, substantially as described.

3. In combination, a printing press having a form, an ink distributing plate, and a roller movable from one to the other to transfer ink from the plate to the form, the plate comprising a plurality of movable sections with meeting edges interfitting when engaged and completely separated when disengaged whereby to prevent the formation of an ink line on the roller, substantially as described.

4. The combination with a printing press having a form, an ink distributing plate, and a roller movable from the plate to the form to transfer ink from one to the other, the ink plate comprising a plurality of sections movable toward and from each other in a direction which is parallel to the axis of the roller and having interfitting elements on the meeting edges of the sections such as to prevent the formation of an ink line when the sections are engaged, there being a clearance in the direction of roller travel between such elements when the sections are completely separated, substantially as described.

HERMAN ADOLPHUS AGRICOLA, Jr.
